(57) **CLAIM**

The ornamental design for a co-axial cable compression connector, as shown and described.

DESCRIPTION

FIG. 1 is a perspective view of a new and ornamental co-axial cable connector in a open position, with portions shown in phantom for illustrative purposes only and forming no part of the claimed invention;

FIG. 2 is a top plan view thereof, the bottom plan and side elevational views all being mirror images of the top plan view;

FIG. 3 is a nut end view thereof; and

FIG. 4 is a cable end view thereof; and,

FIG. 5 is a perspective view of an alternate embodiment of the present design showing a flange extending from one end and thereof, the flange being illustrated in phantom for illustrative purposes only and forming a part of the claimed invention.
